(57) **CLAIM**

The ornamental design for a disposable waste containment receptacle, as shown and described.

DESCRIPTION

FIG. 1 is a perspective view of a disposable waste containment receptacle of our new design;

FIG. 2 is a front view thereof;

FIG. 3 is a side view thereof;

FIG. 4 is a top view thereof; and,

FIG. 5 is a bottom view thereof.

The receptacle is shown with a symbolic break in its length. The appearance of any portion of the article between the break lines forms no part of the claimed design.
